DESIGN FOR A SHAVING BRUSH

Irving Florman, New York, N. Y.

Application February 6, 1940, Serial No. 90,072

Term of patent 14 years

To all whom it may concern:

Be it known that I, Irving Florman, a citizen of the United States, residing at New York, in the county of New York and State of New York, have invented a new, original, and ornamental Design for a Shaving Brush, of which the following is a specification, reference being made to the accompanying drawing, forming a part thereof.

Fig. 1 is a top plan view of a shaving brush showing my new design;

Fig. 2 is a side elevational view thereof with the top portion shown in Figs. 1 and 3 omitted, and the brush in elevated position; and

Fig. 3 is a side elevational view of the brush shown in Figs. 1 and 2, in closed position, the article being rotated 90° from the position shown in Fig. 2.

I claim:

The ornamental design for a shaving brush, substantially as shown.

IRVING FLORMAN.
